UNITED STATES PATENT OFFICE.

ELIZABETH AMENT, OF LOS ANGELES, CALIFORNIA.

WINDOW-SHADE ROLLER.

1,244,403.

Specification of Letters Patent. Patented Oct. 23, 1917.

Application filed May 21, 1917. Serial No. 170,093.

To all whom it may concern:

Be it known that I, ELIZABETH AMENT, a citizen of the United States, residing at Los Angeles, in the county of Los Angeles and State of California, have invented new and useful Improvements in Window-Shade Rollers, of which the following is a specification.

This invention relates to a window shade 10 roller and particularly pertains to means for fastening the shade upon the roller.

One of the most objectionable features to the use of window shades of common construction has been that when the shade is entirely unrolled it often is drawn from its mounting upon the roller. The principal object of this invention is to provide effective means for securing the shade in its mounted position so that it is not liable to 20 become loose under any circumstances.

Another object of this invention is to provide fastening means which embody an end flange adapted to guide the shade and permit it to roll straight.

It is a further object of this invention to provide a combined fastener and roller flange which is composed of few parts, inexpensive in their construction and readily adapted to be mounted upon the roller.

Other objects will appear hereinafter.

The invention is illustrated, by way of example, in the accompanying drawings in which:

Figure 1 is a view in perspective illustrating the shade roller in its assembled condition with a portion of the shade broken away to more clearly set forth the detail construction of the fastener.

Fig. 2 is a view in transverse section as 40 seen on the line 2-2 of Fig. 1 illustrating the arrangement of the shade upon the fastener.

Fig. 3 is a view in perspective illustrating one of the fasteners disassociated from the 45 roller.

Referring more particularly to the drawings, 10 indicates a window shade roller, cylindrical in section, and preferably formed of wood. This roller is of the 50 spring roller type having a cylindrical trunnion 11 at one end and a flat sided trunnion 12 at its opposite end, the uses of which are obvious. Mounted at the opposite ends of the roller are fastening elements 14. These 55 elements, as particularly shown in Fig. 3, are formed with a tubular sleeve 15 adapted

to fit snugly over the end of the roller and an out-turned flange 16 which lies at right-angles to the axis of the roller. These parts are made of thin gage metal so that tacks 60 may pierce through the sleeve without difficulty. Secured to the sleeve at a point adjacent the flange 16, is a fastening clip 17. This clip is only fastened to the sleeve at one end, its opposite end being free and extending outwardly from the end of the sleeve. The clip is preferably tapered from its fastening position. Mounted upon the roller is a shade 18, the upper end of which passes over the roller, around the clip 17, as 70 indicated by the portion 19, and thereafter back between the shade and the clip, as indicated by the numeral 20 where it is secured by a series of tacks 21 which are driven through the end of the shade and 75 thereafter successively through the clip, shade and sleeve into the roller.

When the fasteners 14 are to be used they are slipped over the ends of the roller with their sleeve portions extending inwardly, 80 after which the shade is positioned around the roller and caused to over-lap the clip portion 17, as particularly indicated by the dotted lines of Fig. 2. The shade portion 20 is then tacked to the roller by means of 85 the tacks 21. When this has been done the body of the shade is passed over the clip to assume the position indicated by the solid lines of Fig. 2. This method of mounting insures that the shade will be held in a 90 vertical position in relation to the roller and that it will not readily become torn at the edges.

It will thus be seen that the window shade roller here disclosed as fitted with the special fasteners, provides simple positive means for securing the shade and also guide flanges for insuring that the shade will roll straight.

While I have shown the preferred form 100 of my window shade roller as now known to me, it is evident that various changes in the combination, construction and arrangement may be made by those skilled in the art 105 without departing from the spirit of my invention.

I claim:

1. A fastener for window shades, comprising a sleeve adapted to be positioned around the end of a window shade roller, a clip 110 formed upon said sleeve and around which the ends of the shade may be wrapped, and

means for simultaneously fastening the shade and clip against the side of the roller.

2. A fastener for window shades, comprising a sleeve adapted to be positioned around the end of a window shade roller, a clip formed upon said sleeve and around which the ends of the shade may be wrapped, means for simultaneously fastening the shade and clip against the side of the roller, and an annular flange formed upon said sleeve to guide the shade as it is wound upon the roller.

3. A window shade fastener, comprising a sleeve adapted to be positioned around the ends of a window shade roller, a clip formed upon said sleeve and extending longitudinally along its side, said clip being fastened to the sleeve at the outer end thereof and adapted to permit the end of a shade

roller to be wrapped around it, and fastening means for simultaneously securing the shade and sleeve to the roller.

4. A window shade fastener, comprising a sleeve adapted to be positioned around the ends of a window shade roller, a clip formed upon said sleeve and extending longitudinally along its side, said clip being fastened to the sleeve at the outer end thereof and adapted to permit the end of a shade roller to be wrapped around it, fastening means for simultaneously securing the shade and sleeve to the roller, and an annular flange formed around the outer end of the sleeve adjacent the mounting point of the clip.

In testimony whereof I have signed my name to this specification.

ELIZABETH AMENT.
